[57] CLAIM

The ornamental design of a golf club putter handle and shaft,
as shown and described.

DESCRIPTION

FIG. 1 is a front elevational view of a golf club putter handle
and shaft showing my new design;

FIG. 2 is a right side elevational view thereof, the undis-
closed opposite side being a mirror image;

FIG. 3 is a rear elevational view thereof; and,

FIG. 4 is a top plan view thereof.
